UNITED STATES PATENT OFFICE.

GEORGE HOWLETT DAVIS, OF WEST ORANGE, NEW JERSEY.

AUTOMATIC MUSIC-SHEET-GUIDING DEVICE FOR SELF-PLAYING MUSICAL INSTRUMENTS.

1,082,849.

Specification of Letters Patent.

Patented Dec. 30, 1913.

Application filed June 30, 1908. Serial No. 505,201.

To all whom it may concern:

Be it known that I, GEORGE HOWLETT DAVIS, citizen of the United States, residing at West Orange, in the county of Essex and 5 State of New Jersey, have invented certain new and useful Improvements in Automatic Music-Sheet-Guiding Devices for Self-Playing Musical Instruments, of which the following is a specification.

10 My present invention relates to and has for its object to provide a new and improved form of automatic music roll guiding device for self-playing musical instruments. Devices for this and similar purposes are now 15 in general use. The majority of them are intricate and expensive and cannot be relied upon in all conditions of their operation, being extremely liable to get out of order.

These devices, over which the present invention 20 is an improvement, comprise a tracker board which is moved transversely of the moving music sheet by an intricate mechanical mechanism operated through the agency of either pneumatic or electrical means.

25 This mechanism is automatically controlled by the deviation of the music sheet from its proper position as respects the tracker bar by means of pneumatic valves or electrical contacts adjacent the edge or longitudinal

30 margin of the sheet and located generally on the tracker bar or board. In the case of the pneumatic control, an aperture communicating with the pneumatic operating means is located at each end of the tracker

35 bar adjacent the end of the sheet and normally the sheet covers these apertures. Upon the deviation of the sheet to one side of its normal position, the aperture is opened and the mechanism is operated to move the tracker bar itself underneath the music sheet so as to restore the music sheet and tracker bar to their proper relative positions. In effect this is a follow-up

40 mechanism, and it will, of course, be obvious 45 that it is necessarily cumbersome and stiff in operation, as well as hard to adjust. In the case of the electrical control, contacts are located in position similar to the apertures in the tracker bar for the pneumatic control, and these contacts are normally separated

50 from coöperating contacts for closing an electrical circuit by the interposition of the edges of the music sheet. A deviation of the music sheet to one side or the other enables 55 the contacts to come together and close an

electrical operating circuit. Other devices there are which instead of moving the tracker bar bodily move the music sheet by moving the spools and take up rolls or by moving the music sheet by shifting a flanged roller over which the sheet is caused to pass 60 during its passage over the tracker bar.

My present invention obviates entirely all intricate or cumbersome mechanism of the above mentioned types, and provides a 65 simple and practical mechanical mechanism which is light, durable and quick acting, and which engages both edges of the traveling note sheet and automatically keeps the perforations in perfect alinement with the apertures of the tracker bar, although the sheets may vary greatly in width at different 70 points in their length.

To these ends my invention consists of a pair of guiding members located one at each 75 end of the tracker bar and biased toward each other by means acting on a lever mechanism connecting them together, the mechanism being so constructed that it acts differentially on the moving music sheet. This 80 differential action of the lever mechanism is most advantageous in that it greatly quickens the action of the device.

My invention will be readily understood 85 from the following description and accompanying drawings in which the detail structural advantages are set forth along with the above named features.

In the accompanying drawings, Figure 1 is an elevation of my improved mechanism 90 shown in connection with the tracker bar of a musical instrument of ordinary construction. Fig. 2 is a plan view of the same with the addition of the ordinary form of delivery and take up spools. Fig. 3 is a transverse, vertical section taken through line A—A of Fig. 1. Fig. 4 is a plan view of a different form of my invention from that shown in Figs. 1, 2 and 3, and Fig. 5 is a 95 sectional end elevation of the same. 100

Like numerals apply to the same parts in all the illustrations.

My preferred method of carrying out my invention is to pivotally attach to each side of the tracker bar the two bell crank levers 105 1, 1', the horizontal arms 2, 2' of which are pivotally connected at point 3. These horizontal arms are normally kept against the stop 4 by a spring 5 attached at one end to the levers and at the other end to an ad- 110

justing screw 6 attached to the side of the tracker bar. Plate springs 6' are provided on the underneath sides of the horizontal arms of the levers and press them forward 5 against the tension of spring 5, thus annulling the effect of the weight of the horizontal arms of the levers and so acting against the spring 5 as to enable one to make a very delicate adjustment of the 10 biasing force of the springs 5.

Across the vertical arms 7, 7', of the levers at each end of the tracker bar I secure guide plates or members 8, 8', which preferably project beyond the sides of the tracker 15 board in order to provide a considerable length of bearing surface for the edges of the paper. This extended bearing surface prevents undue wear or mutilation of the edges, especially when the paper is rather 20 thin and there is a tendency for it to wrinkle due to the pressure exerted on it by the guide members. I prefer to notch the tracker bar at the point 9, so that the lower 25 edges of the plates 8, 8', will be below the upper edge of the tracker board. Although I prefer to do this as it avoids accidental slipping of the edge of the paper beneath the guide plate, it is, of course, evident that it is not absolutely necessary, and there are 30 instances when a location of the guide plates with their lower edges flush or even above the edge of the tracker board will be desirable.

The device as described is adjusted with 35 respect to the tracker board with extreme care, so that the inner surfaces of the guide plates 8, 8', will be at all times precisely equidistant from the center of the tracker bar or from the outer apertures 11, 11'. The 40 music sheet, of course, is usually of a width such that when its middle point is over the middle point of the tracker bar, the apertures in the tracker bar and the perforations in the sheet register. A variation in these 45 conditions would have to be made, of course, by a variation in the position of the guide members or plates to the right or left.

12 is the take up roller which is permanently alined with the tracker bar and its 50 apertures so as to draw the paper over the tracker bar in the proper path.

The spools upon which the note sheets are wound and which form the delivery roller when in the instrument vary slightly in their 55 dimensions. Especially do different makes vary. In order to ascertain whether any one spool is in alinement with the tracker bar and the take up roller as it should be, I project from one or both of the guide plates 60 8, 8' an arm 13 which bears against the inner edge of one of the flanges 14 of the said spool or delivery roller at such time as the note sheet is tracking properly, and by spreading the plates away from the edges of 65 the note sheet, or allowing said plates to

bear upon such edges, the device readily indicates whether the delivery spool or roller is in proper alinement or not. If the arm 13 is made sufficiently stiff, it will serve to aline the spool or delivery roller. It is obvious that this arm 13 may project into the path of the flange of the takeup roller 12, where of course it will serve to aline the takeup roller. On rewinding the music sheet 17 upon the delivery roller or spool, 70 this arm 13 serves to properly aline the delivery roll, so that the music sheet and the roll will be kept in proper alinement, so that no matter in which direction the music sheet is traveling, the arm 13 serves to keep 75 the sheet and the rollers, upon which it is wound, in the proper alinement.

The operation of my device is substantially as follows: The music spool is inserted in the bearings 15^a provided for it and the free end 16 of the note sheet 17 is secured to the take up roller 12 in the usual way. When in operation the note sheet will be drawn taut over the tracker board between the guide plates 8, 8', which are 80 forced by the music sheet slightly apart, the width of the sheet being a little greater than the normal distance between the guide plates. The guide plates then bear delicately against the adjacent edges of the paper. As they are connected together, the pressure on each edge of the paper will normally be the same if the note sheet is of 85 the same width from end to end or does not deviate from its proper path over the 90 tracker board, the spring 5 acting on both 95 levers at the same time. As the instrument is played, the take up roller 12 revolves in the direction of the arrow 20 causing the note sheet 17 to travel over the tracker 100 board, the commonly used drag or retarding device acting against the paper or its 105 delivery roller in its forward movement. As long as the paper travels in perfect alinement, then the guide plates 8, 8' bear 110 against its edges with equal pressure as above stated, but as soon as it travels to one side; due to any cause, say to the right side, the guide plate 8' is forced momentarily a very slight distance, possibly a 115 sixty-fourth of an inch to the right. At the same time the pressure on the guide plate 8 on the left is removed, and hence the entire tension of spring 5 will be exerted through lever 2', the plate 8' on the 120 right edge of the sheet thus forcing the sheet back into its proper path where the perforations in the sheet are in alinement with the apertures in the bar. As the plate 8 on the left is at this moment free from 125 the edge of the paper, the latter is easily forced back to the left when the plate 8 will again act on the edge of the sheet, and each plate will then exert an equal pressure 130 against the respective edges of the sheet.

This pressure as has been heretofore mentioned can be adjusted as delicately as desired. In this manner the two guide plates are kept in constant motion. Their effect is a differential one. The release of pressure on the one guide plate causes an increased biasing force to be applied to the other guide member or plate, and as long as the paper is in contact with both plates the greater the deviation toward one of those points, the greater the force tending to restore the sheet to its normal position. In normal operation the action on the sheet is scarcely perceptible as the sheet is in constant motion over the tracker board and the movement of the guide members is small, the differential action causing a quick correction of slight variations. The levers at the point 3, however, can be seen constantly in motion. The springs 6' which are used beneath the horizontal arms of the levers may be dispensed with in some instruments, such for instance as those in which the tracker board is vertically or obliquely disposed.

In Figs. 4 and 5 is shown a different form of my invention. This form is particularly adapted for use in instruments where the note sheet passes over the tracker board in a plane disposed substantially vertically. In this modification 30 is the tracker bar. On the upper side of this tracker bar is secured a long bar or strip of metal 31, the ends of the bar being bent down in such a manner that they form feet for the attachment of the strip to the tracker bar and support the strip so that its surface is inclined at an angle with the surface of the side of the tracker bar to which it is secured. As shown, this inclination is toward the back of the tracker bar. The levers 2, 2' are pivoted to the strip 31 and carry on their short arms the guide members or plates 32 in a position to engage the edges of the note sheet prior to or just after its passage over the tracker bar, depending upon the direction of movement of the note sheet. The guide members are of a trapezoidal shape and their engaging surfaces are of such an extent as to minimize the danger of crinkling the edge of the note sheet. The long end of the levers are connected together by a pin and slot connection 33 and 33' respectively. In the normal operation of the device, the weight of the long ends of the levers 2, 2' tends to draw them down the incline of the strip 31, and biases the guide members 32 toward each other in a manner entirely similar to that of the first form of my invention described. If necessary to overcome friction or to increase the biasing force of the guide members, I may use a weight 34 attached to the pin 33, as shown, or to one or both of the levers 2, 2'. Of course, the use of this

weight depends entirely upon the delicacy of adjustment and the amount of biasing force desired. The weight of the levers alone will be enough in cases where delicate adjustment is desired and the note sheet moves easily over the tracker bar, being itself light and not stretched so taut that it bears against the tracker bar with a great pressure. In case the note sheet is heavy and is stretched very taut it may be desirable to use a weight of such size as will give the result desired.

While I have described the best form of my invention now known to me, it is of course obvious that the skilled mechanic may make many modifications in the construction without departing from its generic spirit. In the annexed claims I desire to cover all such modifications.

What I claim is,—

1. In combination, a tracker bar and pivoted guide plates adjacent to each end of said bar, spring mechanism for biasing said plates toward each other and toward the center of said bar, and a connection between said plates for causing the same to move in unison. 85

2. In combination, a tracker bar, a pair of levers pivoted to the side of the bar, a connection between said levers causing them to move in unison, guide members on said levers adjacent the ends of said bar, and means biasing the levers to draw the plates toward each other. 95

3. In combination, a tracker bar, guide members adjacent each end of the tracker bar, a lever mechanism on said bar acting on said members, and means acting on the mechanism to bias the members toward each other. 100

4. In combination, a tracker bar, guide plates adjacent each end of said bar, a lever mechanism to which said guide plates are connected, means acting on the mechanism to bias the plates toward each other, 110 and means acting on the mechanism in opposition to said biasing means. 105

5. In combination, a tracker bar, means for passing a music sheet over said bar, guide plates adjacent to each end of said bar, spring mechanism for biasing said plates toward each other and for increasing the biasing force exerted upon one plate upon the deviation of the sheet from its proper path. 115

6. In combination, a tracker bar, means for moving a music sheet over said bar, guide plates adjacent to each end of said bar, said plates having portions extending beyond the sides of said bar and spring mechanism for biasing said members toward each other. 125

7. In combination, a tracker bar, means for moving a note sheet over said bar, guide members for the sheet on said bar, a connec- 130

tion between said guide members for causing the same to move in unison and means connected to one of said guiding members for determining the alinement of said note sheet moving means.

8. In combination, a tracker bar, means for moving said note sheet over said bar comprising a take-up roll and a note sheet roll, guide members mounted on the ends of said tracker bar, a connection between said guide members for causing the same to move in unison and gravity actuated mechanism connected to one of said members for determining the alinement of said note sheet roll.

9. In combination, a tracker bar, means for moving a note sheet over said bar comprising a takeup roll and a note sheet roll, guide members in normal engagement with the opposite edges of the note sheet, when the same is tracking properly on the ends of said tracker bar, a connection between said guide members for causing the same to move in unison, and an arm connected to one of said members for contact with said note sheet roll for determining the alinement thereof.

10. In combination, a tracker bar, means for moving a note sheet over said bar, comprising a takeup roll and a note sheet roll, guide members in normal engagement with the opposite edges of the note sheet, when the same is tracking properly on the ends of said tracker bar, a connection between said guide members for causing the same to move in unison, and an arm connected with one of said rolls for determining the alinement of said roll.

11. The combination, with a traveling sheet or web, of a tracker-bar, and guiding means, which include resilient means normally inoperative, applied to the sheet or web adjacent the tracker-bar to push or bodily move the sheet or web into normal relation with the tracker-bar when the diverging sheet presses against the guiding means.

12. The combination, with a traveling sheet or web, of a tracker-bar, and guiding

means carried by the tracker-bar, which include resilient means normally inoperative, applied to the sheet or web adjacent the tracker-bar to push or bodily move the sheet or web into normal relation with the tracker-bar when the diverging sheet presses against the guiding means.

13. The combination, with a traveling sheet or web, of a tracker-bar, and guide fingers connected with resilient means normally inoperative, applied to the sheet or web adjacent the tracker-bar to push or bodily move the sheet or web into normal relation with the tracker-bar when the diverging sheet presses against the guide fingers.

14. The combination, with a traveling sheet or web, of a tracker-bar and guide fingers carried by, and applied to the sheet or web adjacent to the tracker-bar, and connected with resilient means normally inoperative, to push or bodily move the sheet or web into normal position, when the diverging sheet presses against the guide fingers.

15. The combination, with a traveling sheet or web, of a tracker-bar, guide fingers carried by, and applied to the sheet or web adjacent to, the trackerbar, and resilient means normally inoperative connected with the guide fingers to push or bodily move the sheet or web into normal relation with the tracker-bar, when the diverging sheet presses against the guide fingers.

16. The combination, with a traveling sheet or web, of a tracker-bar, guide fingers carried by, and applied to the sheet or web adjacent to the tracker-bar, and springs normally inoperative attached to the guide fingers to press same against the edge of the diverging sheet or web to push or bodily move the sheet or web back into normal relation with the tracker-bar.

In testimony whereof I affix my signature in presence of two witnesses.

GEORGE HOWLETT DAVIS.
